HOLDING TRAY FOR A GLUE BOTTLE AND ARTIFICIAL EYELASHES

Mehron Melik, 150 W. 46th St., Elmhurst, N.Y.

Filed Nov. 15, 1963, Ser. No. 77,448

Term of patent 14 years

(Cl. D86—10)

Fig. 1

Fig. 2

FIGURE 1 is a perspective view of a holding tray for a glue bottle and artificial eyelashes, embodying my new design.

FIGURE 2 is a plan view thereof.

The dominant features of my design reside in the combination in a tray of an elongated rectilinear groove of uniform width and rounded ends parallel to and adjacent one long side of the tray, a varying depth recess of generally truncated semi-conical form adjacent one short side of the tray terminating at its smaller end in a reduced recess portion that extends normal to, across and beyond the rectilinear groove adjacent one end thereof and of a depth greater than the depth of the rectilinear groove, and a pair of identical longitudinally spaced arcuate recesses extending between the rectilinear groove and the other long side of the tray, with corresponding arcuate walls thereof being of different curvature, and each arcuate recess terminating in a flat end wall parallel to each other and to the long side of the tray, all as shown.

I claim:

The ornamental design for a holding tray for a glue bottle and artificial eyelashes, as shown and described.
